(57) **CLAIM**

The ornamental design for a firearm grip sleeve, as shown and described.

DESCRIPTION

FIG. 1 is a perspective view of a firearm grip sleeve in a position of use on a firearm according to the present design.

FIG. 2 is a right elevation view of the firearm grip sleeve shown in FIG. 1.

FIG. 3 is a left elevation view of the firearm grip sleeve shown in FIG. 1.

FIG. 4 is a rear elevation view of the firearm grip sleeve shown in FIG. 1.

FIG. 5 is a front elevation view of the firearm grip sleeve shown in FIG. 1.

FIG. 6 is a top elevation view of the firearm grip sleeve shown in FIG. 1.

FIG. 7 is a bottom elevation view of the firearm grip sleeve shown in FIG. 1.

FIG. 8 is a perspective view of a firearm grip sleeve in a position of rest according to a first embodiment of the present design.

FIG. 9 is a top elevation view of the firearm grip sleeve shown in FIG. 8.

FIG. 10 is a bottom elevation view of the firearm grip sleeve shown in FIG. 8.

FIG. 11 is a right elevation view of the firearm grip sleeve shown in FIG. 8.

FIG. 12 is a left elevation view of the firearm grip sleeve shown in FIG. 8.

FIG. 13 is a front elevation view of the firearm grip sleeve shown in FIG. 8.

FIG. 14 is a rear elevation view of the firearm grip sleeve shown in FIG. 8.

FIG. 15 is a perspective view of a firearm grip sleeve in a position of rest according to a second embodiment of the present design.

FIG. 16 is a top elevation view of the firearm grip sleeve shown in FIG. 15.

FIG. 17 is a bottom elevation view of the firearm grip sleeve shown in FIG. 15.

FIG. 18 is a right elevation view of the firearm grip sleeve shown in FIG. 15.

FIG. 19 is a left elevation view of the firearm grip sleeve shown in FIG. 15.

FIG. 20 is a front elevation view of the firearm grip sleeve shown in FIG. 15; and,

FIG. 21 is a rear elevation view of the firearm grip sleeve shown in FIG. 15.

(Continued)

The broken line showing of a firearm in FIG. 1 is for the purpose of illustrating environment and forms no part of the claimed design.
